UNITED STATES PATENT OFFICE

FRANK N. GILBERT, OF BINGHAMTON, NEW YORK

POCKET PENCIL AND PEN HOLDER

Application filed March 5, 1928. Serial No. 259,309.

The present invention relates to a holder adapted to be carried in the pocket, and has for its object to facilitate the carrying of cigars, pencils, pens and memorandum papers and other articles to be convenient for use. This invention provides a case, and admits the easy insertion of these articles, which will hold cigars against breakage, and hold pencils and protect the point of the same and also prevent injury to the pocket from contact with the pencil point; it also holds memorandum slips or other papers in position for immediate use when the case is open, and the clothing is protected, and when removed from the pocket it opens like a book.

With these objects in view my invention consists in certain novel features of construction and arrangement of parts, as will be hereinafter fully described and pointed out in the claims, reference being held to the accompanying drawings in which:

Fig. 1 is a plan view of a pocket holder, constructed according to this invention the holder being unfolded.

Fig. 2 is an edge view of the holder, partly unfolded, and certain parts being omitted.

Fig. 3 is an edge view of the holder partly unfolded.

Fig. 4 is a perspective view of a part of my device.

Fig. 5 is a perspective view of a holder in open position ready for use.

Fig. 6 is an end view in cross section of the device folded.

Fig. 7 is an edge view of a modified form of the device partly unfolded.

The same reference characters denote like parts in each of the several figures of the drawings.

A designates the body portion of the holder which is in form of a flat strip of leather or reinforced paper, or other suitable material or combination thereof. This body portion A is folded into substantial folds of equal length to form folds or sections 3, 3', 3'', 3''', 3'''', the folded portion of the body between the sections 3', 3'' is folded inwardly on the line 4. As a further part of my invention I have the sleeve 5 shown in Figs. 3 and 4, with its folded over ends 6, 6, the sleeve 5 is slipped

over the folded sections 3'', 3''', 3''''', as shown in Figs. 3 and 7, the ends 6, 6 are folded over together on the back side of the section 3'', as shown in Fig. 6, and Figs. 3 and 7, and the device when folded by the reason of the crimp or crease formed by the folding of the ends 6, 6 over on the part 5 forms a secure sliding sleeve or binder, designed to slip down and rest with its lower edge in line with the fold between 3'' and 3'''; and in this position the sliding sleeve 5 while subject to yield in opening as shown in Fig. 6 for the insertion of articles either between the outside face of the binder 5 or between the folds 3'' and 3''', yet the overlapped ends 6, 6, are held firmly by the pressure of the section 3', because of the stiffness of the material it will not permit of an opening or loosing of the folds 3'', 3''', and 3''''', so as to permit of the loss of articles in these pockets.

Attention is respectfully called to applicant's previous patent, dated August 9th, 1921, No. 1,386,700, but in this form of applicant's device, there are certain new and important novel features added to the invention.

In a modified form of my invention, the flat strip of material is divided into four equal lengths or sections instead of five sections as shown in Fig. 1; in this latter form shown in Fig. 7, the section 3''''', being omitted, which simplifies the construction as shown in Fig. 7. Section 3''' and the sections thus folded, folds over on sections 3'' and sections 3'' is folded over on section 3'. Then the sleeve 5 is slipped over the folds 3'', and 3''' and 3'''' or as in the modified form as shown in Fig. 7, it is slipped over the folds 3'', and 3''' and the folded ends 6, 6 of the sleeve press against 3' or strip A, which in this position holds the sleeve in secure grasping engagement, around the folds 3'' to 3'''' of the body A. In this position the sleeve 5 forms with its securely folded formation, a pocket in which the folded sections of strip A are the sides of the pocket and pencils may be slipped between the folded sections 3'' and 3''', and cards and papers slipped in between the outer face of section 3'''' or 3''' as shown in Fig. 7, and the inner face of the sleeve 5, 100

thus adjacent pockets are formed by the folds and the sleeve with its sliding open ends 6, 6 permits a yielding pocket opening adapted to removably receive articles of varied thickness, but the ends 6, 6 of the sleeve, by reason of their length prevent a disengagement of the sleeve from the folds, and thus the pocket is held secure. The case is closed by folding the outer section 3 over on the inner sections 10 3"" or 3", the sides or faces are 3" and 3" as shown in Fig. 2, form inclined guides adapted to receive the pens or pencils, and direct them into place between these folds and pencil points may rest in the pocket of 15 the case between the section 3" and 3", at the line of fold; while sleeve 5 inclosing the folds prevents the pencils from slipping out at the side, and in a similar way cards or memorandum papers are held.

20 Having thus described my invention what I claim as new, and for which I desire Letters Patent is as follows:

21 1. A pocket holder comprising a strip of flexible material folded intermediate its ends 23 to form a plurality of sections, the first and second sections of the folded strip forming the cover with the other folded sections adapted to be folded between the cover sections, and a sleeve slidably mounted over the 25 folded sections between the covers, said sleeve being formed with overlapping free inner ends which are pressed together between the cover sections.

22 2. A pocket holder comprising a rectangular flat body portion formed of flexible sheet material adapted to be folded transversely into sections of equal length to provide inner sides and covers for the holder and an inelastic sleeve slidably mounted over the 40 inner sides, said sleeve formed with overlapping disengaged inner ends and constituting the ends for the holder.

23 3. A pocket holder comprising a flat strip folded on transverse lines to provide inner sides and covers for the holder, and an inelastic sleeve slidably mounted over the inner sides between the covers, said sleeve having lapped ends disposed between adjacent folds and forming the ends of the holder.

50 In testimony whereof I have affixed my signature.

FRANK N. GILBERT.
